CANDLE

Mary C. Hussey, Mount Vernon, N. Y.

Application October 18, 1945, Serial No. 623,047

3 Claims. (Cl. 67—22)

1

This invention relates to wax candles—the term "wax" being used generically to include the various waxes and known equivalents therefor adapted for candle making. The invention is particularly useful for decorative candles and is designed to prevent disfiguration or destruction of the decorative effect, even when the candle burns for considerable periods of time.

In the burning of candles, difficulty is encountered caused by what is termed "guttering." This defect is caused by accumulation of molten wax in the form of a small pool which eventually extends to the edge of the candle, and then drips or runs down outside the body of the candle, rendering it unsightly and often even disfiguring the furniture, or the table pieces.

It is an object of this invention to construct candles of a novel decorative or fanciful design which will burn for relatively long periods of time without disfiguration or destruction of the decorative value of the candle. To that end it is also an object of the invention to eliminate run-off of molten wax to the exterior of the candle by providing a run-off channel as a part of the decorative design.

In the accompanying drawings which form a part of this specification:

Figure 1 is a front view in perspective of one form of the invention;

Figure 2 is a vertical sectional view of the candle of Figure 1 taken along the line 2—2 looking in the direction of the arrows.

The drawings reveal clearly how these objects of the invention are attained. The body of the candle—that portion situated between the points 10 and 11, 12 and 13 and 14 and 15 of Fig. 2, has a wick 16 centrally located in the body and forms a structure much like the ordinary candle. The novel feature of the construction herein disclosed resides in the fact that helical convolutions designated by 17, 18, 19, 20, 21 and 22 of the same or similar wax material as that of the body have been disposed thereabout and in such manner as to form deep channels or gutters at and above the points 10 to 15 of Fig. 2. It will be recognized that the configuration of the convolutions is much the same as in the well known Archimedian screw devised by Archimedes to pump water to higher levels by mere rotation of a helical tube or channel.

The upper edges at the top of the convolutions as indicated by the reference characters 17 and 18 preferably project above the central body portion of the candle situated between the above mentioned points 10 and 11, thus forming a rela-

2

tively deep pool to hold the molten wax when the candle is first lighted. This prevents the wax from flowing over the edges 17 and 18. The molten wax as fast as it accumulates in the pool flows down the two independent channels, one channel defined by reference characters 10, 13, 14, the other channel defined by reference characters 11, 12 and 15. The entrances to the channels, one of which is shown at approximately the point 10, are at the bottom of the pool and between the tip of the candle body, when first lighted.

In the construction shown in the drawings the body of the candle is enveloped in two distinct sets of convolutions. One may be said to start at the point 11 above and terminate at the point 23 below, where it merges with a base 24, likewise of wax, upon which the candle may be supported. This convolution thus makes nearly two complete turns around the main body of the candle. The second convolution may be said to start at the point 10 above; it joins and merges with the base at a point diametrically opposite the point 23, and therefore back of the candle where line 22 merges into base 24 at a point not visible in these views.

Two downwardly sloping channels are thereby provided, on two opposite sides of the main body of the candle, at all points from its upper to its lower extremity. Whenever the wax becomes molten and sufficiently fluid to move by gravity, it finds its way to one or the other of these helical channels and trickles downward until it becomes sufficiently cooled to cease flowing. The molten wax congeals before it has flowed very far, and may pile up in the descending channel so as to partly fill it, as shown at 25 in both Figs. 1 and 2. The exterior bank of the channel, for example that at or near point 19, hides the accumulated run-off of the wax at all points except to vision directed downwardly at the candle. In any event its exterior surfaces retain their original appearance at all times, except that, of course, the total height gradually decreases as the upper layers are burnt away and transformed into gas and vapor.

It will be understood that instead of using two convolutions as illustrated herein, I may substitute either one or three or more helical gutters for run-off of molten wax, and the gutters may make any desired number of turns about the candle depending upon its length. Other changes may be made in the precise design without departure from the spirit of my invention.

The novel candle may be formed in any suit-

able manner as by being cast in a mold with the base 24 uppermost, and then extracted from the mold by turning the solidified candle about its axis so as to unscrew it, so to say, from the mold.

I claim:

1. A decorative wax candle comprising a body, a wick in the body, and an Archimedian channel of deep downwardly inclined form enveloping the body from top to bottom to form a run-off gutter for molten wax.

2. A decorative wax candle comprising a body, a wick in the body, and a plurality of Archimedian channels of deep downwardly inclined form enveloping the body from top to bottom to form run-off gutters for molten wax.

3. A decorative wax candle comprising a body, a wick in the body, and helically disposed convolutions enveloping the body and forming deep downwardly inclined channels between the convolutions and the body, the upper edges of the convolutions extending upwardly around the top of the body and forming a pool for collecting the wax and directing it into the downwardly inclined channels.

MARY C. HUSSEY.
